AUTOMATIC WORK CLAMP AND LENGTH GAUGE

Benjamin G. Hardy, Merchantville, N. J., assignor to Albert P. De Sanno, Jr., Philadelphia, Pa.

Application December 2, 1931, Serial No. 578,500

4 Claims. (Cl. 29—69)

My invention relates to a machine employed for cutting metal, marble or any similar hard substance and relates particularly to the manner of holding the material or stock to be cut.

Heretofore, the locking of the stock, so that it may be cut, has been done manually by the operator; hence, considerable time has been required to lock the stock in place, to measure the length of the piece to be cut, and to dispose of the material after it has been severed from its parent piece.

It is an object of my invention to automatically lock the stock in the vise by the same manual operation used to perform the cutting, and so reduce the cutting time by permitting rapid set-ups.

Another object of my invention is to construct a device which automatically permits the machine to be cleared of the severed piece and which also permits the ready adjustment of the length of the material or stock for the new cut.

Another object of my invention is to provide a mechanism whereby the release of the cutter opens the jaws of the vise, permitting the short stock previously severed to drop when the remaining stock to be cut is placed in position.

Another object of my invention is to provide a mechanism for placing the movable portion of the machine in a neutral or balanced position.

With the above objects in view my invention consists of a cut-off machine having a rotating cutter, a vise to retain the material that is to be cut and which is automatically locked by the same movement which performs the cutting, a gauge which regulates the length to be cut, and means to release the severed piece.

Other objects of my invention are to provide an improved device of the character described, that is easily and economically produced, sturdy in construction and having a maximum efficiency and accuracy.

With the above and related objects in view, my invention consists in the details of construction and combination of parts, as will be more fully understood from the following description, when read in conjunction with the accompanying drawings in which:

Fig. 1 is a perspective view of a cut-off machine embodying my invention.

Fig. 2 is a perspective view of the vise in which the piece to be cut is held.

Fig. 3 is the bottom perspective view of the gauge.

Fig. 4 is a fragmentary sectional view of the pointer.

Fig. 5 is a side elevational view of the mechanism for placing the machine in a neutral position.

Fig. 6 is a plan view of the vise and gauge; and Fig. 7 is an enlarged view of the rod arm and its mounting on the movable cutter section of the machine.

Referring more specifically to the drawings, I show a machine wherein steel, steel alloys, other metals and non-metallic materials may be quickly, coolly and accurately cut. The machine is composed of a base A, a rotating cutter and movable support B, an automatic clamping vise C mounted upon the base A; and an adjustable measuring device and holder D.

The base A carries the automatic clamping vise C and has pivoted to its lower extremity a movable support B which carries the rotating cutter 10.

The automatically closing vise C has a fixed 20 lower jaw 12 and a movable jaw 14, which slides on a plurality of guides 16 and 18. A groove 20 in the jaws exposes the stock or material so the cutter 10 can cut the original piece while the work is held rigidly. However, the parent piece 25 and the severed piece of material are still gripped after the cut is complete.

To the forward side of the movable jaw 14 is an extension 22 having an opening wherein a rod 24 is fastened by a lever operated locking or 30 set screw 26. However, the rod 24 may be shifted in the opening of the extension for purposes of adjustment. A crankarm or pitman 28, pivotally connected at its ends to the rod 24 and a crank 29, moves the rod and the extension 22 35 whenever a crank shaft 30, which carries the crank 29, is oscillated. The crank-shaft 30, suitably mounted in a bearing is attached at one end to a lever 32 which moves upward when a riding wheel or stud cam 34 contacts with the free end of the lever 32. A strong tension spring (not shown) is placed under the riding wheel or cam 34 to relieve the strain thrown on the lever 32.

The stud cam 34 is attached to the front of the support B, to one side of the cutter 10, and directly in front of an opening 36 in the support B. Forward movement of the support B causes the stud cam 34 to raise the lever 32 and thus clamp the jaws 12 and 14 about the stock or material M as more fully hereinafter described.

Upon moving the cutter away from the work the dropping of the lever 32 rotates the crank 45 backwards, thereby releasing the work and per-

mitting the work to be moved forward into position for another cutting operation.

To provide a measuring device, when material is to be cut rapidly, I provide a scale arm 38 and a measuring clamp or device, generally designated as D, see Figs. 1, 3 and 6. The measuring device D is adapted to be adjustable both longitudinally and transversely relative to the scale arm. These adjustments are optionally accomplished by releasing and locking the bolts 42 and 40 on the longitudinal and transversely movable elements 44 and 46, respectively. An arm 48 is pivotally mounted at 49 on the transversely adjustable element 46.

A rod 50 with an eye formed at one end is attached to the arm 48 between the pivot 49 and the free end, by means of an eye bolt in the side of the arm.

A stud 56 of a general U-shape formation is attached to a guard 52 for the cutter. The rod 58 is adapted to slide within the trough of the U-shaped stud 56. However, an adjustable stop clamp 54 is positioned upon the rod to the rear side of the stud. The stop clamp is adjusted upon the rod in order that the pivoted arm 48 will be raised out of the path of a longitudinal movement, in a right hand direction, of the material within the vise. However, such action, that is: the raising of the arm 48, will occur because of the arrangement of parts when the movable support B is normally reclining at the limit of its rearward stroke, as is well-known in Figure 1. Therefore, if the material severed is sufficiently long its release from the right hand vise jaws, as viewed in Figure 6, will enable it to drop since the arm 48 will no longer support the free end of the severed material. If the material severed is short and will not drop because of the support afforded it by the lower right jaw of the vise such short piece of material may easily be pushed out of the vice.

When the handle 72 is moved forward a short distance the arm 48 is allowed to move into position against the transverse element 46, and movement of the material to be cut within the vise jaws and against the tip of the pivoted arm determines the length of the material which will be cut. It is to be observed that the forward movement of the support B enables the U-shaped stud 56 to slide idly along the rod 50, thus, coaction between the stud and the stop clamp will occur only upon the rearward stroke of the support B.

The length of material to be cut (when inserted in the vise and against the tip of the arm 48) is predetermined by moving the measuring device D on the scale arm 38 until the pointer 58 on the measuring device is positioned adjacent the length designation desired. When the material is inserted in the vise and against the tip of the arm 48 and then severed it will be of the predetermined length as indicated on the scale. To provide for variations in thickness of cut-off discs I provide for the variation of the zero position of the pointer 58. One offset-end of the pointer 58 is movable within a bore 62, see Figs. 4 and 6, on the longitudinal movable element 44. A spring-pressed ball engages one end of the pointer 58 which is within a complementary bore. The bore 62 and the complementary bore are interconnected at a suitable angle. Thus, the spring-pressed ball provides the retaining force or pressure for keeping the pointer in position, nevertheless as the pressure exerted on the pointer is not unduly high the

pointer may still be moved by the person operating the machine. In other words, the tension exerted by the spring 64 on the ball which engages the pointer is only sufficient to prevent the pointer from being jarred loose by the vibration of the machine when in operation.

The movable support B which carries a motor is pivotally mounted, as at 66, near its lower end to the base A. The motor is positioned to one side of the dead center of the support and so tends to swing the support B backwards or counterclockwise because of its weight.

The support B, however, is limited in its movement, because of a spring 74 and a nut 70 on an eyebolt 68 whose eye is suitably secured to the base A. The eyebolt 68 passes through an opening in the support B, and has the manually adjustable nut 70 on the threaded end thereof. The nut 70 is adjusted in a neutral position so that but a minimum quantity of energy need be utilized to shift the cutter by the handle 72. The spring 74 is placed about the eyebolt 68 between the support B and the nut 70 to minimize shock. By turning the screw 70 a long or short stroke of the cutter 10, on the support B may be made, whereby the time of shifting the cutter may be controlled.

The closer the wheel 10 is to the material then the less tension or strain of the vise jaws on the material held therein. By so regulating the grip of the vise jaws the crushing of tubing or soft solids is prevented.

To prevent the lever 32 from dropping too low, so that it would not be engaged by the riding wheel or stud cam 34 when the support B is moved forward, I provide a rest or stop 76 suitably located and in this particular embodiment of my invention the stop 76 is placed adjacent to the lever arm 32, to limit the downward movement of the lever.

A guide or metal chute 78 to engage a projection (not shown) on the fixed base A is placed beneath and adjacent to one end of the vise, and directs the material cut to a suitable receptacle.

A summary of the operation of my invention is as follows:

The length of stock to be cut being predetermined, the adjustable measuring device and holder D is moved upon the scale arm 38 until the pointer 58 indicates the desired length on the scale arm.

The handle 72 is pulled slightly forward and the stock is moved forward by the operator so that the material touches the arm 48. Further movement of the arm 72 clamps the work in the vise through the elevating of the lever 32, which turns the crankshaft 39, thereby oscillating the crank 29, the pitman 28, and the rod 24, closing the jaw 14. The material is locked while the cutter 10 revolves and cuts through the material.

When the cutting is completed, the releasing of the arm 72, by the operator, permits the cutter 10 on the support B to move backward, thereby releasing the movable vise jaw and pushing the stop clamp 54 backwardly to elevate the arms 48 permitting the piece cut to drop on the chute 78 and into a basket or receptacle.

It is to be noted that the arm 48 may be positioned to engage the center of various sized materials by the adjustment of the movable elements 44 and 46 as well as a set screw 79. The set screw is situated on the transverse shiftable element 46 and engaged by the arm 48, so that when the screw is extended the arm is likewise extended.

When a new cutter 10 of different thickness is

used it is necessary to recalibrate the scale. This is readily done by moving the element 44 toward the cutter until the arm 48 just contacts with the cut-off disc. The adjustable pointer 58 is then moved until it coincides with the scale zero.

5 A helical tension spring 80 has one end attached to the fixed base A and its other end is attached to the arm 32. The spring 80 is attached to the arm 32 intermediate the points 10 where the crank-shaft 30 joins the arm 32 and the cam stud 34 engages one end of the arm 32; the force of the spring 80 reacts to pull the arm 32 downwardly. Hence, the jaws of the vise normally are kept open.

15 The lever 32 may be shifted forward or backward by virtue of a slot therein, on the crank-shaft 30 when the retaining nut is loosened in order to accommodate a long or short stroke of the cutter.

20 Although the invention has been described in considerable detail, such description is intended as illustrative rather than limiting, as the invention may be variously embodied, and the scope of the invention is to be determined as claimed.

25 I claim:

1. In combination with a vise, a gauge for measuring the length of material to be cut comprising a scale, a longitudinally shiftable member mounted on said scale, a transversely shiftable member mounted on said first named member, an adjustable pointer on said first named member cooperable with said scale to designate the position where said first named shiftable member should be placed relative to said scale.

30 2. In a cut-off machine having in combination a movable support carrying a rotatable cutter, a vise including a fixed jaw and a movable cooperating jaw, said vise suitably mounted adjacent said movable support, a shaft rotatably

mounted adjacent said vise, a cam stud mounted on the movable support, an arm connected to said shaft and adapted to be moved by engagement with said cam stud, a crank arm also connected to said shaft and to one end of a pitman, and a rod connected to the other end of the pitman and associated with the movable jaw of the vise whereby upon movement of the arm which cooperates with the cam stud the movable jaw of the vise will be moved either in a closed or in an open 10 position.

3. In a machine for cutting stock; a gauge for measuring the length of stock to be cut comprising a scale; a longitudinally shiftable member mounted on said scale; a transversely shiftable member, having means thereon which is adapted to abut said stock, and mounted on said first named member; and a pointer on said first named member co-operable with said scale to designate the position where said first named 15 shiftable member should be placed relative to said scale.

4. A gauge for measuring a length of material to be cut comprising a scale, a longitudinally shiftable member mounted on said scale, a transversely shiftable member mounted on said first named member, a pivotally mounted arm carried by said transversely shiftable member, and said pivotally mounted arm adapted to abut the material to be cut, a pointer adapted to register with said scale mounted on said longitudinally shiftable member, and means to permit adjustment of said pointer relative to said longitudinal shiftable member, said transversely shiftable member being positioned on said longitudinal member in 30 order to centrally locate said pivotally mounted arm with respect to the material to be cut.

BENJAMIN G. HARDY.
